Charles L. Wright.

UNITED STATES PATENT OFFICE.

THEOPHILUS H. REINHARDT AND JOSEPH A. MERKLER, OF STATEN ISLAND, NEW YORK.

GARMENT SUPPORTER.

1,402,878.

Specification of Letters Patent. Patented Jan. 3, 1922.

Application filed March 18, 1921. Serial No. 453,468.

To all whom it may concern:

Be it known that we, THEOPHILUS H. REINHARDT and JOSEPH A. MERKLER, both citizens of the United States, and residents of Staten Island, in the county of Richmond and State of New York, have invented certain new and useful Improvements in Garment Supporters, of which the following is a specification.

10 The principal purpose of this invention is to produce a clip engageable with the upper end of a stocking or like article in a secure manner without damage to the same, the clip being attached to the tape, preferably elastic, secured in any convenient manner to other garments or a band worn for that purpose.

Another object is to provide devices having cushioned gripping jaws capable of being 20 widely opened for the insertion of the articles to be supported, or instantly clamped tight upon it so as to prevent slipping, but without tearing or otherwise damaging the article.

25 A still further object is in the provision of clips shaped to conform to the limb encased in the supported article by being suitably curved, thus being worn with entire comfort and presenting no unsightly projection.

These and other objects, such as neatness of appearance, ease of attachment and adjustment, durability and cheapness of construction are attained by the novel construction, combination and arrangement of parts hereinafter described and shown in the accompanying drawings, forming a material part of this disclosure and in which:—

Figure 1 is a perspective view of a clip 40 made in accordance with the invention, shown in an open position and drawn to an enlarged scale.

Figure 2 is a plan view of the same, shown closed and indicating the manner in which 45 it is supported.

Figure 3 is a side elevational view thereof.

Figure 4 is a central longitudinal sectional view.

Figure 5 is a bottom view.

50 Stated briefly in general terms, the device consists of a thin flat plate, its upper end containing an elongated transverse slot suited to receive the supporting tape and its lower

end extended on both sides to a suitable width, curved to present a concave rear surface approximating the limit against which it will be adjacently disposed. 55

The lower and end edges are turned outwardly forming a socket receptive of a rubber cushion having a longitudinally ribbed 60 face and above the socket are a pair of lugs acting as hinge elements for the clamping jaw.

This jaw agrees with the lower element in dimensions and like it is provided with 65 a socket carrying a cushion complementary to the other, and between which the supported article is clamped.

A lever, pivoted on the plate, has an offset portion adapted to make contact with the 70 outer surface of the clamp element, the other end of the lever acting as a handle by which it is operated and means are provided to maintain the lever when adjusted in a clamping position. 75

Referring now more particularly to the drawings in detail, the numeral 10 designates a metallic body having a neck 11 merging into a head 12 pierced by an elongated transverse slot 14 in which is secured a tape 80 15 attached at its upper end to any preferred support.

The base 16 is concavely curved to a radius approximating the limit of a person and has its marginal edges raised forming the walls 85 17 and 18 of a socket having secured therein a block 19 of elastic material provided with a central longitudinal raised rib 20.

A pair of lugs or ears 22 are formed with the side edges of the plate 10 at points above 90 the socket, these lugs being perforated to receive pintles 24 formed on opposite sides of the leaf or clamp jaw element 25 curved in accordance with the base, and carrying, in a socket formed by the walls 26 and 27, 95 respectively end and bottom, another elastic block 28 having ribs 29 complementary to the rib 20.

In a plane above the lugs 22 and at a point central of the body plate 10 is a raised boss 100 30 having on its upper seat surface, a lever 31 pivoting on the rivet 32 passing through the lever and boss and being upset at both ends.

The front or lower end 33 of the lever is offset and adapted, when positioned 105 lengthwise the device, to press upon the con-

vex outer surface of the clamp element 25, forcing the cushions 28 and 19 yieldingly toward each other.

The upper end of the lever 31 has an out-turned end 34 adapted to act as a handle in operating the lever, which may be turned in either direction as may be most convenient and when off the clamp element allows the latter to be raised to the fullest extent.

10 In order to maintain the lever in clamping position and stress the clamp by the resilient effect of the lever when central upon it to the limit, a raised bridge 35 is extended across the neck 11 and at the center of it 15 is a depression 36 receptive of the lever and when extended lengthwise, the upper surface of the bridge being outwardly inclined from its ends toward the center.

The rear element of the fastener is preferably provided with a lining or outer covering 40, made of any suitable material, as cloth, felt or chamois leather, the same preventing the metallic parts of the clasp from making direct contact with the person of 25 the user.

In operation, the lever is turned crosswise of the clip, freeing the clamp jaw which is raised and the article to be supported entered so as to be engaged by the cushion 30 whereupon the lever is rotated upon its axis, one end pressing the clamp resiliently downward, while the other end of lever mounts the bridge and snaps into the depression by which it is held against accidental displacement.

35 Due to the relatively large area of the cushion surfaces and their curvature, an entered article is firmly secured and the clip worn with entire comfort.

40 As changes of construction could be made within the scope of the invention, it is intended that all matter contained in the foregoing description or shown in the accompanying drawings shall be interpreted as 45 illustrative and not in a limiting sense.

Having thus described our invention, what we claim as new and desire to secure by Letters Patent, is:—

1. An article of the class described, comprising a plate, a clamp element pivoted thereon, said plate and clamp being curved concavely at the back of the article, longitudinally ribbed cushion elements disposed in said plate and clamp a raised boss on said plate, a lever pivoted on said boss, said lever having an offset portion contactable with said clamp, and means on the opposite end of said lever by which it may be operated. 50

2. An article of the class described, comprising a plate, having side extensions on its broadened lower portion, said plate being curved longitudinally, lugs formed with said plate, a clamp element pivoted in said lugs extending over the lower portion of said plate and bent in conformity to it, a lever 60 pivoted on said plate having a part engageable with said clamp, sockets formed in said plate and clamp element, elastic cushions in said sockets, and a raised transverse element formed with said plate having 65 inclined surfaces adapted to stress said lever when moved thereover. 70

3. An article of the class described, comprising a plate curved longitudinally at its lower inclined portion, a clamp element 75 hingedly engaged to said plate, said clamp being curved in conformity to said plate, a resilient lever pivoted on said plate, said lever having an offset end engageable over the convex surface of said clamp, a rib on 80 the upper end of said plate, said rib having inclined surfaces contactable with the other end of said lever, and means in said rib adapted to engage said lever when in operative position. 85

In testimony whereof we have signed our names to this specification.

THEOPHILUS H. REINHARDT.
JOSEPH A. MERKLER.
